Rudolf Busch, Mainz, Germany, assignor to
David Kaufmann, Nuremberg, Germany

Application May 16, 1935, Serial No. 56,863
In Germany March 18, 1935

Term of patent 7 years

To all whom it may concern:

Be it known that I, Rudolf Busch, a citizen of Germany and resident of Mainz, Germany, have invented a new, original, and ornamental Design for a Deck of Playing Cards, of which the following is a specification, reference being had to the accompanying drawing, forming part thereof.

The drawing shows plan views of five cards, namely an ace, a king, a queen, a jack, and one of the pip cards, these five cards having been selected as typical of the complete deck of cards.

I claim:

The ornamental design for a deck of playing cards, as shown and described.

RUDOLF BUSCH.
